RECEPTACLE

William J. De Witt, Auburn, N. Y., assignor to Shoe Form Co., Inc., Auburn, N. Y., a corporation of New York

Application August 13, 1938, Serial No. 224,723

6 Claims. (Cl. 220—20)

This invention relates to an improvement in receptacles and more particularly in circular receptacles having a plurality of compartments accessible at the periphery and including a plurality of elements, at least one of which being adapted to be rotated relative to the other elements.

The primary object of this invention is to provide a receptacle comprising a circular box having a plurality of radially arranged sector-shaped compartments and means for closing all of said compartments or permitting access to the interior of a selected compartment, such means including an element relatively rotatable with respect to the box.

A further object of this invention is to provide around such circular box a band relatively rotatable thereto, said band having an opening adapted to be brought by such relative rotation 20 into register with the mouth of a selected compartment and a door for such opening.

These and other objects of this invention will appear from a consideration of the following description and of the drawings which form a part 25 thereof and in which:

Fig. 1 is a perspective view of one embodiment of the invention;

Figs. 2 and 3 are longitudinal sectional views thereof, showing the embodiment of Fig. 1 with 30 a selected compartment opened and closed respectively;

Fig. 4 is a cross-sectional view taken along the line 4—4 in Fig. 1;

Fig. 5 is a cross-sectional view taken along the 35 line 5—5 in Fig. 2;

Fig. 6 is a view in side elevation of another embodiment of this invention;

Fig. 7 is a longitudinal cross-sectional view of the embodiment shown in Fig. 6 with a selected 40 compartment open;

Fig. 8 is a view in edge elevation with parts broken away, with the compartments closed;

Figs. 9 and 10 are detail views in cross section taken along the section lines 9—9 and 10—10 respectively in Fig. 6;

Fig. 11 is a view in side elevation of another embodiment of the invention, portions thereof being broken away and the door of one compartment being open;

Fig. 12 is a view in edge elevation of the embodiment shown in Fig. 11, all compartments being closed but the door of one being free to be opened; and

Fig. 13 is a transverse sectional view taken 55 along the line 13—13 in Fig. 11.

The flybox 20 (selected as the embodiment to be illustrated in Figs. 1 to 5 inclusive) comprises a cylindrical box 21 having a plurality of sector-shaped radial compartments 22 defined by the side walls 23 and a plurality of radially arranged partitions 24. The walls 23 and partitions 24 are preferably made of transparent material so that the contents of the compartments are visible at all times. As shown in Fig. 5 the walls 23 are provided with radiating corrugations 25 in which the edges of the partitions are received and secured. The side walls 23 terminate at their peripheries in flanges 26 which define U-shaped grooves or channels 27.

Surrounding the box 21 is an annular band 30 the side edges of which are received in the channels 27. The band 30 is provided with an aperture 31 and with a door 32 slidable to open or close the aperture. The band 30 and door 32 may also, like the walls 23 and partitions 24, be made of transparent material if desired. The ends of the band overlap, as shown in Figs. 2 and 3, and the outer end 33 serves to limit the movement of the door in one direction, at which time the aperture 31 is closed. As best shown in Fig. 4, the edges of the door 32 ride in the channels 27 outside the edges of the band. The movement of the door to open the aperture is limited by a transverse rib 34 raised from the surface of the band 30. In order to hold the door in the closed position there is provided on the band between one edge of the aperture 31 and the rib 34 a second rib 35, which is preferably lower than the rib 34 so that the door can be slid thereover and which engages the rear edge of the door.

The surface of the door 32 is preferably crowned except at the edges so as to reduce to the minimum any resistance to its movement around the band. It will be noted that, during the main travel of the door, the rib 35 is below the crowned surface 36 of the door (see Fig. 2). Suitable means are provided by which the door 32 is slid to open or close the aperture 31, such for example as a boss or button 37 formed at the center of the door.

It is customary with flyboxes of this type to suspend them from the belt or a buttonhole of the fisherman. For this purpose applicant provides a snap hook 38 attached to the band 30 by a bar 39. The bar 39 has a raised central portion and is preferably secured at the overlapping ends of the band where the band is stiffest.

The compartments 22 are adapted to contain flies, lures, hooks and the like. The box suspended by the hook 38 can be readily tilted so

that the contents of the compartments are seen through the transparent walls 23. Upon determining the compartment which contains the desired article the box is rotated until the mouth 5 of the compartment is in register with the aperture 31 in the band 30. The door 32 is then slid to open the aperture and afford access to that compartment. After the desired article has been removed the door is again closed to avoid the 10 possibility that any of the contents of the flybox will fall out inadvertently.

The flybox 50 shown in Figs. 6 to 10 inclusive like the flybox 20 comprises a cylindrical box 51, having a plurality of pie-shaped radial compartments 52 defined by side walls 53 and a plurality of radially arranged partitions 54, which are received and secured in suitable corrugations 55 in the side walls (see Fig. 9). The peripheral edges of the walls 53 are bent to provide flanges 56 and 20 grooves similar to the construction described above.

Surrounding the box is a band 60 which rides in the circular tracks defined by the flanges 56 and grooves 57. As shown particularly in Fig. 7 the ends of the band are spaced apart a distance approximately equal to the distances between the partitions at the mouths of the compartment. The band 60 when placed as shown in Fig. 7 affords access to a compartment and the space between the ends of the band will hereinafter be designated for convenience as an aperture 61. The band 60 carries a door 62 having an aperture 63 therein which may be brought into register with the aperture 61. The walls 53, partitions 56, band 60 and door 62 are preferably though not necessarily made of transparent material. Secured to or formed upon the band 60 is a button 64 which projects into the aperture 63 in the door and thus limits the opening or closing thereof. A similar button 65 on the door facilitates such movement of the door. The side edges of the door 62 ride between the side edges of the band 60 and the flanges 55.

The flybox 50 is suspended by any suitable means as by a snap hook 66 pivotally attached by a strap 66 to a rivet 67 fixed at the center of one side wall 53. As shown in Fig. 10 the rivet 67 is mounted in a sleeve or collar 68 secured to the inner face of the side wall portions of the partitions 54 having been removed to provide a pocket 69 which accommodates the sleeve or collar. While the pocket 69 is open to the compartments 52 at the tip thereof the space between the sleeve or collar 68 is such that there is no danger that the contents of one compartment will escape into another compartment.

In using the flybox 50 the box and band are rotated to bring the compartment containing the desired article to the top. The band 60 is then slid around the box to bring the aperture 61 therein into register with the mouth of that compartment. The door 62 is then slid along to open the compartment by bringing the apertures 63 and 61 into register so that the contents of that compartment are accessible.

Figs. 11, 12 and 13 illustrate another embodiment of this invention in the form of a receptacle 70. The receptacle 70 comprises a box 71 having a plurality of radially arranged compartments 72. The compartments 72 are formed by side walls 73, a central tube 74 and a plurality of radially extending partitions 75. The walls 73 are provided with ribs or corrugations 76 in 75 which the edges of the tube 74 and partitions 75

are seated and secured by suitable adhesive or cement.

The peripheral edges of the side walls are bent to form flanges as shown in Fig. 13. The lower wall is bent upwardly and downwardly to form a peripheral groove 77 and flange 78 and then outwardly to form an outer flange 79 at right angles to the flange 78. The upper wall is bent downwardly and then upwardly to form a peripheral groove 80 and flange 81. Each compartment 72 is closed by a door 82 here shown as mounted upon leaf hinges 83 fixed to the flanges 78 and 79. The side edges of the door 82 rest against the edges of the partitions 75 which in part define the compartment. The other edge rests against the flange 81. Spring means such as the spring wire 84 may be provided to hold the door normally closed.

The doors 82 are locked closed by a plate 85 fixed upon one end of a post 86. The post 86 extends through the center of the box 71 and is enlarged at the end opposite to that secured to the plate 85. The plate 85 has a peripheral flange 87 which extends downwardly over the edges of the doors 82. The flange 87 is interrupted to provide an aperture 88 somewhat longer than the width of the door. When, as shown in Fig. 12, the plate is so set that the flange aperture 88 is in register with the door 82 of a compartment, the door 82 may be swung open so that the contents of the compartment are accessible.

The receptacle 70 is so formed that it may be placed upon a table or suitable supporting surface or may be used as a flybox being suspended by the use of suitable means such as the hook 65 and strap 66 described above. The compartment containing the desired fly or the like is first determined by visual inspection through the walls or doors, when as is preferred all or most of these elements are made of transparent material. If the flybox is supported on a horizontal surface the plate 85 is rotated to bring the flange aperture 88 in register with the door of the selected compartment. If the flybox is suspended the box is rotated on the post 86 until the selected compartment is uppermost and thereafter the cover 85 is turned until the door of that compartment is released.

While several embodiments of this invention have been shown and described in detail it will be understood that the invention is not limited thereto and that other embodiments may be made without departing from the spirit and scope thereof as set forth in the following claims.

I claim:

1. The combination with a circular box having side walls and radial partitions secured thereto and forming therewith a plurality of sector-shaped compartments open at the periphery of the box, the periphery of the side walls having flanges which extend over the ends of said partitions and annular track-forming grooves adjacent said flanges, of a band around the periphery of the box and rotatable relative thereto, the side edges of the band being received in said grooves, the band having an aperture therein adapted to register with the mouth of any compartment, a sliding door on said band, the edges of said door being received in said grooves, said door being adapted to open and close said aperture and thus control access to the compartment with which the aperture is brought into register by the relative rotation of box and band, and means rotatably secured to the box at the center thereof by which means the box is suspended.

2. The combination with a circular box having side walls and radial partitions secured thereto and forming therewith a plurality of sector-shaped compartments open at the periphery of the box, the periphery of the side walls having flanges which extend over the ends of said partitions and annular track-forming grooves adjacent said flanges, of a band around the periphery of the box and rotatable relative thereto, the side edges of the band being received in said grooves, the band having an aperture therein adapted to register with the mouth of any compartment, a sliding door on said band, the edges of said door being received in said grooves, and said door having an aperture therein which, in one position of the door, registers with the aperture in the band, whereby when the aperture of the band is brought by the relative rotation of box and band into register with a selected compartment, the sliding door of the normally closed door to a position in which the aperture therein is in register with the aperture in the band permits access to the interior of the selected compartment.
3. The combination with a circular box comprising side walls and radial partitions secured thereto and forming therewith a plurality of sector-shaped compartments open at the periphery of the box, the side walls terminating in flanges which extend beyond the ends of the partitions and in which annular track-forming grooves are formed, of a band surrounding said box, the side edges of the band being received in the grooves, so that box and band are relatively rotatable, the band having an aperture therein adapted to register with the mouth of any compartment, a sliding door on said band, the side edges of said band being received in said grooves, said door being movable over the band to open and close said aperture and being guided in its movement by said grooves, the surface of the door being crowned except at the edges which ride upon the band, and a rib in the band adjacent the aperture, which rib, during main travel of the door, is below the crowned surface thereof and, when the door is fully opened, engages the forward edge of the door and, when the door is fully closed, engages the rear edge thereof.
4. The combination with a circular box comprising side walls and radial partitions secured thereto and forming therewith a plurality of sector-shaped compartments open at the periphery of the box, the side walls terminating in flanges which extend beyond the ends of the partitions and in which annular track-forming grooves are formed, of a band surrounding said box, the side edges of the band being received in the grooves, so that box and band are relatively rotatable, the band having an aperture therein adapted to register with the mouth of any compartment, a sliding door on said band, the side edges of said band being received in said grooves, said door having an aperture therein and being movable over said band to bring its aperture into register with the aperture in the band and thereby afford access to the compartment with which the aperture in the band is in register, a button on said band which projects into the aperture in the door and thus limits the movement of the door in both opened and closed positions.
